STATION SELECTION BY PRINTER
SELECTOR

David S. Hulfish, Chicago, Ill., assignor to Teletype Corporation, Chicago, Ill., a corporation of Delaware

Application January 17, 1938, Serial No. 185,341

15 Claims. (Cl. 178—2)

The present invention pertains to telegraph communication systems and more particularly to such systems involving a plurality of stations arranged with instrumentalities for their selective interconnection for telegraph communication.

An object to be attained by the invention is a method of operation of such a system to effect transmission of messages, which involves a minimum number of operative steps preparatory to transmission of intelligence and subsequent to the conclusion of the transmission of intelligence.

A further object of the invention is the provision of simple and reliable circuits and mechanisms for enabling any station of a telegraph system to select another station or plurality of stations with which it is desired to communicate.

A still further object of the invention is to enable an originating station to establish, before and during operations of selecting a desired station or stations, conditions by which all stations of the system are prevented from interrupting an established communication or the processes of establishing a connection for communication.

Another object of this invention is to provide automatic means for answer-back communication such that when a station has responded to its calling code signal transmitted from a controlling station, a response signal or answer-back signal shall be transmitted upon the connecting line and recorded at the controlling station.

It is a further object of the invention to effect disconnection of all operating stations and release of all disabled stations by a single controlling step which may be performed at any operating station.

Further features of the invention reside in the provision of means to manifest at all times the communicative or idle condition of the line circuit as well as the communicative or idle condition of each station apparatus, and to manifest at an excluded station sufficient detail of an existing connection to enable the operator of the excluded station to obtain useful information concerning the state and identity of a communication from which the station is excluded.

The above and other objects of invention are attained by utilizing a plurality of printing telegraph sets each having as a part thereof a motor driven printer selector and a driving motor therefor to which keys, relays, and visual signals are added at each station to effect a method of operation according to the present invention;

namely, that an operator at one station may start all motors to drive all selectors, then by utilizing the printer selector in concomitant function of a station selector may indicate and modify all stations desired for communication, then may disqualify all non-indicated and non-modified stations by stopping their motors or otherwise, after which the indicated stations may intercommunicate between or among those stations exclusively.

A more complete understanding of the invention may be obtained from the following description, taken in connection with the accompanying drawing in which,

Fig. 1 illustrates a line having an indefinite number of connected stations, one station being shown in detail and two other stations being indicated diagrammatically;

Fig. 2 illustrates detail of a snail mechanism for motor control; and

Fig. 3 illustrates an alternative mechanism for motor control.

In Fig. 1 is illustrated a line circuit 10 passing in series through three stations A, C, and E in each of which stations there is provided the following apparatus: a galvanometer 11, a line relay 12, a permutation code signal transmitter 13, a starting key 14, a stopping key 15, and a shunt circuit 16 extending to contact and armature 17 of a selecting relay 18 to disable contact 3 of transmitter 13 and keys 14, 15. A printer selector magnet 20 is connected in a circuit in series with battery 21, slow-to-release relay 22, and contacts of line relay 12, the magnet 20 being provided with a shunt 23 controlled by contact 35 and armature 24 of disabling relay 25.

The printer selector, of which the magnet 20 is a part, may be according to the disclosure of Patent No. 1,904,164 issued to S. Morton et al. In that patent, and specifically in Fig. 27 thereof, there is disclosed selectively operated mechanism which, in response to a letter code, both prints a letter and closes momentarily an electrical contact. Three such elements are shown in Fig. 1; namely, element 30 which will close contact 31 when letter A is printed, element 32 which will close contact 33 when letter Y is printed, and element 34 which will close contact 35 when letter X is printed. The letters printed may be selected arbitrarily but have a relation among the several stations. Contacts Y and X are uniform throughout all stations but element 30 at station C will be associated with the printing of letter C, and element 30 at station E will be associated with printing the letter E.

A keyboard transmitter, indicated by a key lever and code bars 36 is provided at each station and has associated with it at each station a magnet 37 whose armature 38 will depress a single key lever 39. This key lever by its identity will determine the answer-back signal transmitted by a station upon its selection and the answer-back signal may be the same as the calling code signal for the station or may be otherwise as indicated at B, D, and F. A motor 41 is arranged to drive the selector controlled by magnet 20, and also to drive a threaded member 42, Figs. 1 and 2, which engages and moves a snail member 43 to a definitive position wherein the snail member engages and opens a pair of contacts 44. The snail member is urged in rotary manner by a spring 45 and is loosely mounted axially so that it may be rocked transversely by a spring 46 (Fig. 2). The snail member also 10 constitutes an armature member for a magnet 47 and further it may be engaged by a bell crank member 48 pivoted at 49 to be engaged by a power bail 50 at every operation of the power bail for printing purposes. At every printing operation the power bail 50 engages and rotates the bell crank member 48 which, in turn, engages the snail member 43 and lifts the snail member 43 from its screw threaded member 42 thus permitting spring 45 to return the snail member to a starting position, not shown, after which spring 46 draws the screw thread follower point of the snail member into engagement with the threaded member 42. The contacts 44 close an energizing circuit for a motor relay 51 whose contacts close the energizing circuit of the motor 41. A signal lamp 52, preferably colored, is energized by contacts of relay 25 when energized, and a signal lamp 53, preferably white, is energized by contacts of relay 18 when energized.

40 The function of relay 18 is to enable operation of the station by opening shunt 16 thereby qualifying the permutation transmitter 13 and the start and stop keys 14 and 15. The function of relay 25 is to disqualify a station from reception of intelligence by shunting the selector magnet 20. The function of relay 12 is to transmit line signals to selector magnet 20 when that magnet is not disqualified by relay 25 and to transmit line signals to relay 22 at all times, the relay 22 being responsive to signals from keys 14 and 15 but non-responsive to telegraphic intelligence signals from transmitter 13 by reason of its slow-to-release nature. The function of galvanometer 11 is to notify an observing operator whether the line circuit 10 is or is not being utilized for active transmission of intelligence at times when by reason of an energized condition of relay 25 the observing operator is without any means of observation other than the galvanometer 11.

50 Locking circuits are provided for relays 18, 25 and 51 which are closed by the relays at the time of their energization and which may be opened only by slow-to-release relay 22 under control of an operating station.

55 Operation of the apparatus above-described is as follows: Assuming that an operator at station A desires to communicate with station C and to exclude stations E and others connected to the line 10, the operator finds the line in condition of rest with a constant current which produces a steady deflection on all galvanometers 11. At all stations, contacts 17 shunt all contacts 13, 14, 15, and at all stations, a contact 54 in unenergized relay 25 prepares a circuit for energization of relay 18 under control of contacts 55 in key 14.

Operator at station A operates key 14 until motor 41 starts at his station. Operation of key 14 opens the main contacts of the key which, however, are shunted by armature 17 and also closes contact 55 of the key 14 which energizes relay 18 over a circuit from battery, left-hand winding of relay 18, contact 55, contact and armature 54 of relay 25 to ground. Energization of relay 18 opens the contact of armature 17 which, key 14 being held open, opens the circuit of line 10, which reverses all relays 12 and interrupts current through relays 22 at all stations. After a period sufficient to release the armatures of all slow-to-release relays 22, a circuit is closed at every station, including station A, extending from battery, through snail magnet 47, conductor 66, back contact and armature 56 to ground. This attracts all snail members 43 which are returned by springs 45 permitting contacts 44 to engage thus closing at each station an obvious circuit for motor relay 51 which, in turn, closes the energizing circuit of motor 41 including motor 41 at station A. The operator at station A observing the start of his motor releases the starting key 14 which recloses the line 10 and reenergizes all relays 22 which forms an obvious locking circuit for relay 18 at station A, but at no other station because at no other station has relay 18 been energized. Operator at station A now strikes key C of his keyboard transmitter 57 thus transmitting over line 10 a permutation code signal which prints C at all stations, and at station C closes contact 31, which energizes magnet 37 at station C over a circuit which may be traced at station A through battery 58, winding of magnet 37, back contact and armature of relay 18, and contact 31 to ground. Energization of magnet 37 and operation of its armature 38 at station C depresses key lever D and closes a circuit which may be traced at station A from battery, through winding of relay 18, and contact of armature 38 to ground thus energizing relay 13 at station C which forms its locking circuit through armature 56 and opens contact of its armature 17 thus rendering effective its permutation transmitter 13 which, in response to operation of key lever D and code bars 36 at station C, transmits the code signal D upon line 10, which code signal is recorded at all stations including station A. The operator at station C has responded and now is connected to line 10 in condition for reception of intelligence signals. The operator at station A then strikes key lever X in transmitter 57 which prints X at all stations and which at station E and other unselected stations closes a circuit for energization of relay 25 which may be traced in station A from battery, through winding of relay 25, armature and back contact of unenergized relay 18, and contact 35 to ground, but at stations A and C and any other selected station, if A has selected a plurality of stations, the relay 18 is in energized condition and by reason of its open back contact, it will prevent the energization of relay 25 at such station. Energization of relay 25 will illuminate colored lamp 52 at every such station, whereas energization of relay 18 has already illuminated white lamp 53 at each selected station including station A. In each station in which the relay 18 is energized, the permutation transmitter 13 controls the line circuit 10 for transmission of intelligence code signals, and selector magnet 20 is operable in response to line signals because it has not been shunted by armature 24 of relay 25. On the other hand, at stations 75

where relay 25 has been operated and relay 18 has not been operated, no action can occur at the station other than vibration of the indicator hand of galvanometer 11 because at each such station transmitter 13 and keys 14, 15 remain shunted by armature 17 of unoperated relay 18, and magnet 20 is shunted by operated armature 24 of relay 25.

Transmission of intelligence from station A to station C and from station C to station A now may be carried on and at the termination thereof either station A or station C may operate key 15, which will deenergize relay 22 at all stations and after a time delay sufficient to release the armature 56 at all stations, locking circuits of all relays 18 and 25 may be opened, thus relays will be released at all stations, and lamps 52 and 53 will be extinguished at all stations. The operator at station A or C, noting that his lamp 20 is no longer illuminated, may release the key 15 thus restoring all apparatus except snail member 43, relay 51, and motor 41 to the original condition of rest. After an interval of time, the snail member 43 will engage and open its contacts 44 thus deenergizing relay 51, which deenergizes motor 41, restoring all equipment to the original condition of rest. Thus a single act, by key 15, restores to original idle condition both the operative stations and the excluded stations.

30 A station desiring to connect for intercommunication purposes all of the stations on the circuit may do so by the transmission of the code combination of impulses for the letter Y instead of the code combinations for the letters C and X in the example chosen for illustration. The transmission of the code combination of impulses for the letter Y will cause the operation of the pull bar 32 for that letter at each of the respective stations. Closure of the contact controlled by 35 such pull bar will establish an energizing circuit for the electromagnet 37 at each of the stations for the operation of its key bar 39 and the setting of the code bars 36 through which a group of impulses identified with such setting may be 40 transmitted. The operation of the system following the energization of electromagnet 37 is identical with the operation described for the selection of station C. Furthermore, restoration 45 of the system to normal is the same as that previously described for the other selection.

Fig. 3 shows an alternative device for the snail member illustrated in Figs. 1 and 2. When the device in Fig. 3 is utilized, the contacts 44, Fig. 1, are replaced by armature and contacts 60, the 50 magnet 47 is replaced by winding of relay 61, and a circuit 62 extends from winding of magnet 61, through cam contacts 63 operated by a cam 64 fixed to the start-stop selector shaft 65 of the selector controlled by magnet 20, Fig. 1, or the 55 contacts may be operated by a printing bail as 60. Upon release of the armature 56 of relay 22, a circuit is closed through relay 61, conductor 66, and armature 56 to ground, which attracts the armature of relay 61 to close contact 60 substituted for contacts 44 to energize motor relay 51 after which each printing operation under control of magnets 20 rotates shaft 65 and cam 64 one revolution and closes contact 63 momentarily to supply an impulse of current over an obvious 65 circuit to relay 61 thus holding contacts 60 closed throughout transmission of intelligence and permitting contact 60 to open to stop the motor 41 after cessation of transmission of intelligence. The delay period of slow-to-release relay 61 is 70 comparable to the delay period of snail 43.

As applied to printers other than the printer specified in the patent to Morton et al., it will be necessary to apply contacts to letter members upon the printer in any convenient manner and to cause the bell crank 48 or contact members 5 63 to be struck in any convenient manner by any member which is operated in the process of printing each character. Thus, the invention here illustrated may be applied to printing devices of any type.

10 What is claimed is:

1. In a telegraph system, a line circuit, station equipments connected in series in said line circuit, said station equipments including permutation code signal transmitting contacts, and including also shunting contacts connected around the said signal transmitting contacts at all stations of the said line circuit when the line circuit is not in use, and selective means responsive to signals in said line circuit originated by one of 15 said permutation code signal transmitting contacts and operating to open said shunting contacts at others of said permutation code signal transmitting contacts selectively station by station.

2. In a telegraph system, a line circuit, stations connected in series in said line circuit, signaling contacts connected in series in said line circuit, a single shunting contact connected in said line circuit to form a shunt around all of said signaling contacts, and a means manually operable at one station and controlling said shunting contact to remove said shunt from said signaling contacts at said one station.

3. In a telegraph system, a line circuit, stations connected in series in said line circuit, signaling contacts connected in series in said line circuit, shunting contacts connected in said line circuit to shunt said signaling contacts, means at a station manually operable and controlling said 40 shunting contact to remove said shunt from said signaling contacts at said station, and locking means for retaining said shunting contact open after a single operation of said manual means.

4. In a telegraph system, a line circuit, stations connected to said line circuit, signaling contacts at said stations connected in series in said line circuit, shunting contacts connected in said line circuit at said stations to shunt said signaling contacts, a manually operable key at a station having signaling contacts in said line circuit and having further contacts controlling said shunting contacts to remove said shunt from said signaling contacts at said station, and locking means for retaining said shunting contacts open at said 50 station after a single operation of said manual key.

5. In a telegraph system, a line circuit, a plurality of station equipments serially connected in said line circuit including at each station 60 transmitters for intelligence signals, shunt circuits at each station for said transmitter, means responsive to a manually operated key at each station for removing said shunt circuit at said station, and means responsive to a signal in said line circuit for removing said shunt circuit selectively at other stations.

6. In a telegraph system, a line circuit, a plurality of station equipments connected to said line circuit including transmitters at each station for intelligence signals, shunt circuits at each station for said transmitters, manually controlled means at each station for removing said shunt circuit at said station, and means at each station responsive to a signal in said line circuit for 70 75

rendering said shunt circuit unresponsive to said manually controlled shunt removing means.

7. In a telegraph system, a line circuit, a plurality of station equipments connected to said line circuit including transmitters and recorders at each station, manual means at a station for rendering a transmitter and recorder at said station fully operable, signal responsive means at said station for rendering said transmitter and recorder fully operable, and signal responsive means at said station responsive to a signal in said line circuit for rendering non-operable said transmitter, said recorder, and said manual means.

15 8. In a telegraph system, a telegraph line, a plurality of stations connected to said telegraph line, a non-operative transmitter and an operative selector at one of said stations, means at said station for enabling said transmitter, means at said station for disabling said selector, and a signal transmitter at another station for controlling alternatively one or the other of said means.

9. In a telegraph system, a telegraph line, stations connected to said telegraph line, non-operative transmitters and operative selectors at a plurality of said stations, means at said stations for enabling said transmitters, means at said stations for disabling said selectors, and a signal transmitter at another station for controlling alternatively one or the other of said means at said plurality of stations, station by station selectively.

10. In a telegraph system, a telegraph line, a plurality of stations connected in series in said telegraph line, transmitters and selectors at said stations, means in each station for disabling said transmitters, locking means at each station responsive to signals in said line for enabling said transmitters, locking means at each station responsive to signals in said line for disabling said selectors, and means at each station to transmit signals in said line for controlling alternatively one or the other of said locking means at each station.

45 11. In a telegraph system, a telegraph line, a plurality of stations connected to said telegraph line, normally non-operative transmitters and normally operable receiving recorders at said stations, signal responsive locking means at each

station for rendering said transmitters operable, signal responsive locking means at each station for rendering said recorder non-operable, signal responsive means at each station for controlling alternatively one or the other of said locking means at each station, and signal responsive means at all stations, common to both of said locking means at every station, and responsive to a common controlling signal for unlocking both of said locking means at all stations. 10

12. In a telegraph system, a telegraph line, telegraph stations connected to said line, station selector means responsive to signals in said line, and answer-back means responsive to said station selector means and operative by its response 15 to disable itself from further response.

13. In a telegraph system, a telegraph line, telegraph stations connected to said line, station selector means responsive to signals in said line, answer-back means responsive to said station selector means, and means operable by said answer-back means and operating to disable said answer-back means.

14. In a telegraph system, a telegraph line, telegraph stations connected to said line, normally non-operative transmitters connected in said line at said stations, selector means at said stations responsive to signals in said line, answer-back means directly responsive to said selector means at said stations, and means operable by 20 said answer-back means at a station to render said transmitter operable at said station and thereafter to transmit an answer-back signal thereby.

15. In a telegraph system, a telegraph line, 25 telegraph stations connected to said line, normally non-operative transmitters connected in said line at said stations, selector means at said stations responsive to signals in said line, answer-back means directly responsive to said selector 30 means at said stations, means operable by said answer-back means at a station to render said transmitter operable at said station and thereafter to transmit an answer-back signal thereby, and locking means associated with said operable 40 transmitter to maintain said transmitter in operable condition after said answer-back signal has been transmitted.

DAVID S. HULFISH.
